Patented Mar. 19, 1918.

FIG. 1.

FIG. 2.

Inventor

Emry Davis,

By his Attorney

Edgar V. Cole.

UNITED STATES PATENT OFFICE.

EMRY DAVIS, OF BROOKLYN, NEW YORK.

INKSTAND.

1,259,608.

Specification of Letters Patent. Patented Mar. 19, 1918.

Application filed April 28, 1917. Serial No. 165,075.

To all whom it may concern:

Be it known that I, EMRY DAVIS, a citizen of the United States, and residing at Brooklyn, in the county of Kings and State of New York, have invented certain new and useful Improvements in Inkstands, of which the following is a specification, such as will enable those skilled in the art to which it appertains to make and use the same.

10 This invention relates to inkstands of the class shown, described and claimed in U. S. Letters Patent No. 399,844 granted to me March 19, 1889; No. 413,390 granted to me October 22, 1889, and No. 605,177 granted 15 to me June 7, 1898; and the object of this invention is to improve the construction of inkstands of the class shown and described in said patents so as to facilitate the operation thereof, prevent the evaporation of ink, 20 prevent the ink from flowing out if the inkstand is upset, and provide means whereby the inkstand, or the various parts thereof, may be quickly and easily cleaned when necessary; and with these and other objects 25 in view the invention consists in an inkstand of the class specified, constructed as herein-after described and claimed.

The invention is fully disclosed in the following specification, of which the accompanying drawing forms a part, in which the separate parts of my improvement are designated by suitable reference characters in each of the views, and in which:—

Figure 1 is a central vertical section of 35 my improved inkstand and showing the same ready for use; and,

Fig. 2 a similar view showing the method or operation of inking a pen.

My improved inkstand comprises, in the 40 form of construction shown, a well member a , a main float b , a supplemental float c , and a detachable collar d placed within the top of the well member a .

The well member a comprises a main central cylindrical body portion having an enlarged base or bottom a^2 and an enlarged top a^3 in which is a conical recess a^4 through which the main float b is vertically movable and in the enlarged top a^3 is a rabbet groove 45 a^5 in which the collar d is placed.

The collar d is beveled on the top side thereof and forms in connection with the rim a^6 of the enlarged top a^3 and the main float b , when the latter is in the position shown in 50 Figs. 1 and 2, an annular conical recess a^7 ,

and said parts also form below the collar d a similar annular recess a^8 .

The well member a is preferably composed of glass while the main float b , supplemental float c and collar d are preferably 60 composed of hard rubber.

The main float b is hollow and cylindrical in form and open at the bottom and the outer transverse dimensions thereof are only slightly smaller than the inner transverse 65 dimensions of the main reservoir a^9 in the well member a , and the outer transverse dimensions of the main float b are also only slightly less than the inner diameter of the collar d , these differences being such only as 70 to permit of the free vertical movement of the main float b .

The main float b is closed at the top and provided with a conical recess b^2 formed by a conical downwardly directed shell b^3 in- 75 tegral with, or connected with, the top of the main float member and at the bottom of which is a downwardly directed tubular sleeve b^4 which is also open at the bottom and which extends, in the form of construc- 80 tion shown, slightly below the body of the main float b , as shown at b^5 . At the top of the tubular sleeve b^4 forming a communication between the interior of said sleeve and the conical recess b^2 in the top of the main 85 float b is a port b^6 below which is an annular shoulder b^7 , and the supplemental float c is provided with a head c^2 which serves as a valve to close the port b^6 .

The supplemental float c is closed at the 90 top by the head c^2 thereof and said float is tubular in form and open at the bottom where it is provided with an annular enlargement c^3 , the main transverse dimensions of which are only slightly less than 95 the inner transverse dimensions of the sleeve b^4 , and the transverse dimensions of the head c^2 of the float c are slightly less than the corresponding dimensions of the annular enlargement c^3 at the bottom of said sup- 100 plemental float, and said supplemental float is freely movable in the sleeve b^4 and placed in the bottom of the sleeve b^4 is a transverse pin e which prevents the accidental detachment of the float c and holds it in operative 105 position at all times, but said pin e may be removed at any time, if necessary, in order to take out and clean the supplemental float c , and it will be understood also, that the collar d and the main float b may be de- 110

tached from the well member *a* whenever desired for a similar, or for any other purpose.

The transverse dimensions of the port *b*⁶ at the bottom of the recess *b*² in the top of the main float *b* are less than the transverse dimensions of the pen or pens used so that only the point portion of a pen can be passed through said port as shown in Fig. 2 for the purpose of giving the supplemental float *c* an initial depression, but in the operation of passing the pen, or the point thereof, through the port *b*⁶ as shown in Fig. 2, the side edges of the pen, or the body portion thereof, strike the side walls of the port *b*⁶, and this limits the extent to which the pen, or the point thereof is passed through said port, and also depresses the main float *b*, after the initial depression of the supplemental float *c*, and in the use of my invention 20 proved inkstand, the well *a* is filled to about one-third or less of its capacity with ink as shown at *f*, after which the main float *b*, with the supplemental float *c* in position, is passed downwardly into the well *a* through the collar *d* and rests on the ink as shown in Fig. 1, and in the operation of inking a pen, which operation is indicated in Fig. 2, the pen *g* or the point thereof is passed downwardly through the recess *b*² and through 25 the port *b*⁶ onto the head *c*² of the supplemental float *c*, and said supplemental float *c* is depressed, as shown in Fig. 2, as is also the main float *b*, and in this operation the ink passes up through the tube *b*⁴ around the 30 supplemental float *c* into the conical top of the main float *b* as is also shown in Fig. 2, and the pen is inked, and when said pen is withdrawn the float *b* rises and the ink flows back into the bottom of the well through the 35 tube *b*⁴, after which the float *c* rises and closes the port *b*⁶. It will be understood that the pin *e* limits the downward movement of the float *c* and in the above described operation the pressure of the ink in the tube 40 *b*⁴ on the bottom annular head *c*³ of the float *c* holds said float *c* down until the main float *b* rises during which operation the ink continues to flow downwardly around the head *c*³ of the float *c* and said float rises, as above 45 described, when the float *b* reaches the limit of its upward movement.

From the foregoing description it will be seen that while the parts *b* and *c* are described as floats and the part *c* as a float 50 valve, the operation of the part *b* is that of a floating plunger, and it is this floating plunger and its operation, as described, that controls the operation of the entire device.

When the inkstand is not in use, or there 55 is no ink in the well member, the bottom of the float *b*, or the sleeve member *b*⁴ thereof rests on the bottom of the well, and the top of the float *b* is at the point *h*, or at the bottom of the annular recess *a*⁸, and these comparative vertical dimensions of the float *b*

and the well member *a*, the inner walls thereof, are, within certain limits, essential to the successful operation of the device and the lower end portion of the float for at least one-half of its vertical dimensions 70 must closely fit the walls of the well in order to control the flow of ink as hereinafter described, but not so close as to retard the free vertical movement of the float, nor so loose that the film of ink between the float and 75 inner walls of the well will not be held by capillary attraction to prevent the free flow of ink between the float and inner walls of the well when the float is being depressed; and with these dimensions, the top of the 80 float *b*, when the device is in use, will always be above the well, or the point *h* which indicates the top of the well.

In the ordinary use of this device the ink will not rise into the annular recess *a*⁸ nor 85 into the annular recess *a*⁷ but by misuse or carelessness the ink may be forced to rise into these recesses or spaces but will flow back again when the main float *b* rises, and all the parts are so adjusted and fit in such 90 manner that the ink will not flow out of the well if the entire device be upset or turned over, unless it be retained or remain in such upset or turned over position for a considerable length of time, in which event the ink 95 will gradually flow out into and through the annular recesses or spaces *a*⁸ and *a*⁷.

From the foregoing description it will be seen that the air is almost, if not entirely, excluded from the ink when the device is not 100 in use, and while I have shown and described the sleeve *b*⁴ as extending below the bottom of the body of the main float *b*, this is not absolutely necessary, but is done principally to provide for the removal and insertion of the pin *e* and the collar *d* is also not absolutely essential and may or may not be employed, and my invention is also not limited to any particular shape, design or form of the well *a*, and changes in and modifications of the construction herein described may be made, within the scope of the appended claims, without departing from the spirit of my invention or sacrificing its advantages.

It is not absolutely necessary that the float *b* be open at the bottom nor is it absolutely necessary that the float *c* be open at the bottom but the tube *b*⁴ must be open at the bottom, the object of making the top head *c*² 120 of the float *c* smaller than the bottom head *c*³ thereof, or the annular shoulder or enlargement at the bottom of said float is to permit of the free backward flow of the ink around the float *c*, and in this operation the 125 ink strikes the annular shoulder or head *c*³ at the bottom of the float *c* and holds said float down until the float *b* has completed or partially completed its upward movement.

Having fully described my invention, 130

what I claim as new and desire to secure by Letters Patent, is:—

1. An inkstand comprising a well member having a cylindrical reservoir therein, a main cylindrical hollow float vertically movable in said reservoir and provided in the top thereof with a conical recess in the bottom of which is a port, the walls of said conical recess being provided with a tubular sleeve which extends downwardly through the body portion of the main float and in which is mounted a hollow tubular supplemental float open at the bottom and provided at the top with a head adapted to close said port, said well member being also provided with an enlarged top in which is a conical recess through which the main float is vertically movable and in which is placed an annular detachable collar.
2. In an inkstand of the class described, a well member having a cylindrical reservoir open at the top, a main cylindrical float vertically movable in said reservoir and provided in the top thereof with a conical recess at the bottom of which is a port and below which is a tube or bore extending downwardly through said main float and in which is placed a supplemental vertically movable float adapted to close said port the bottom of which is provided with an enlarged annular head.
3. In an inkstand, a main body part having an inner cylindrical well, a cylindrical hollow plunger float closely fitting in said well and vertically movable therein and pro-

vided at the top thereof with a recess at the bottom of which is a port, the walls of said recess being provided with a sleeve which extends downwardly through said float, the vertical dimensions of the float and the depth of the well being approximately the same, a cylindrical valve mounted in said sleeve and adapted to close said port and the bottom of which is provided with an annular enlargement.

4. In an inkstand, a main body part having an inner cylindrical well, a cylindrical hollow plunger float closely fitting in said well and vertically movable therein and provided at the top thereof with a recess at the bottom of which is a port, the walls of said recess being provided with a sleeve which extends downwardly through said float, the vertical dimensions of the float and the depth of the well being approximately the same, a cylindrical valve mounted in said sleeve and adapted to close said port and the bottom of which is provided with an annular enlargement, and said sleeve being provided at the bottom thereof with detachable means for retaining the valve therein.

In testimony that I claim the foregoing as my invention I have signed my name in presence of the subscribing witnesses this 25th day of April, 1917.

EMRY DAVIS.
